UNITED STATES PATENT OFFICE.

WILLIAM T. RUSSELL, OF WELLESLEY, MASSACHUSETTS.

LAMP-GUARD.

No. 914,190.

Specification of Letters Patent.

Patented March 2, 1909.

Application filed January 16, 1908. Serial No. 411,075.

To all whom it may concern:

Be it known that I, WILLIAM T. RUSSELL, a citizen of the United States, residing at Wellesley, in the county of Norfolk and State 5 of Massachusetts, have invented a new and useful Lamp-Guard, of which the following is a specification.

This invention relates to a guard for incandescent lamps.

10 The principal objects of the invention are to provide a metal guard capable of protecting the lamp in a well known manner with a protecting device for the outer end thereof which will be capable of opening to 15 permit access to the lamp without removing the guard and at the same time will permit the guard to be stood on end in stable equilibrium when the protecting device is closed; also to secure this advantage with a simple 20 and inexpensive construction and generally to improve the construction of lamp guards of this character, also to provide for locking the end guard.

Reference is to be had to the accompanying 25 drawings which show preferred forms of the invention and in which,

Figure 1 is a side elevation showing one 30 way in which the invention may be applied to one form of lamp guard; Fig. 2 is a top plan of the end guard. Fig. 3 is an elevation showing a modification with the end guard removed from the body of the main guard, and Fig. 4 is a view of a modification.

The invention is preferably applied to a 35 main lamp guard 10 made chiefly of wire and having a clamping ring 11 for the neck of the lamp. In Fig. 1 this is shown as applied to a form of guard in which two or more springs 12 are located around the inside of 40 the guard to engage the lamp and hold the guard in position thereon. In this form, the two springs 12 are shown as connected at their ends with two or more of the longitudinal wires 13 of which the guard is formed. 45 This is a very simple way of mounting the springs. The guard is provided with the usual central rings 14 and end ring 15, the latter of which is open and is covered by a flat foraminous end guard 16. This end guard 50 is shown as constructed of a ring 17 of wire of substantially the same size as the end ring 15, and covered on one side by a foraminous sheet or wire fabric 18 secured to the ring 17. In the form shown in Figs. 1 and 2, this end

guard is provided with a pair of cross wires 55 19 which are separated from each other at one side of the end guard and are turned up over the wire 17 and bent to form hinges 20 connected with the end ring 15 on which the end guard is adapted to turn. These 60 wires converge toward each other and meet at the other side of the ring 17 where they are turned up to form a catch or hook 21. This catch is adapted to engage the opposite side of the end ring 15 and hold the parts in 65 position. The wires 19 may be separate or integral with each other, the latter construction being shown, the catch 21 and hinges 20 both being integral with the wire 19.

In the form shown in Fig. 3 the foraminous guard is mounted in the same way on the end ring 17 and is provided with a cross wire 22 having projections 23 extending upwardly therefrom to guide the guard into position on the end ring 15. The end guard 75 also is provided with a wire 24 extending across in the other direction and terminating in a pair of hooks or catches 25 preferably integral with the wire, each being adapted to spring over the ring 15 on opposite sides 80 to securely and removably hold the end guard in position. In both cases it will be seen that the foraminous end guard is of such a nature as to protect the end of the lamp and in fact to protect it more completely than it is protected by the side walls 85 of the main part of the guard. Also that the wires 22, 24 and 19 extend across the body of the guard and are fixed to the crossing wires thereof in any desired way as for example, by soldering or by tie-wires 26 so as to serve to strengthen the fabric of the guard and to hold the parts securely in position. These wires also are integral preferably with the catches, hooks, hinges and the like by 90 which the end guard is connected with the ring 15. Moreover, the application of a flat end guard, as specified, to any desired form of lamp guard is accomplished in a very simple and inexpensive manner and the construction is such that the lamp guard can be set up on end and will not have any tendency to tip over and that the end guard can be displaced so that the lamp can be removed if desired.

In order to lock or seal the guard it is provided with a small pad lock 30 or the like or with a seal 31, as shown in Fig. 4. This may

be the same as an ordinary car seal if desired. This constitutes a simple way of preventing the unauthorized removal of the lamp and is especially adapted to this form of guard.

While I have illustrated and described certain forms of the invention as applied to a certain type of lamp guard, I am aware that many modifications may be made in the invention by any person skilled in the art and that it may be applied to many other types of lamp guard without departing from the scope of the invention as expressed in the claims. Therefore, I do not wish to be limited to the particular form of end guard or its application to the particular type of main guard shown, but

What I do claim is:—

1. The combination of an open-ended lamp guard having a circular ring at the end thereof, with an end guard consisting of a circular wire ring of substantially the same size as the end ring, a foraminous wire fabric secured to said ring, and a cross wire secured to said fabric and having means ex-

tending therefrom for securing it to the end ring.

2. An end guard for a lamp guard, consisting of a circular ring, a fabric of cross wires having their ends secured to said ring, and a wire extending across said fabric and having means integral therewith at one end for connecting it with the lamp guard, and a catch integral therewith at the other end for removably attaching it to the lamp guard. 35

3. The combination of a lamp guard having a clamping ring, longitudinal wires and a circular end ring, said guard being open at the end, with a circular foraminous end guard removably mounted on said end ring, 40 and means for securing the end guard to the lamp guard to prevent the unauthorized removal thereof.

In testimony whereof I have hereunto set my hand, in the presence of two subscribing 45 witnesses.

WILLIAM T. RUSSELL.
